LONG ISLAND CITY, NEW YORK, A CORPORATION OF NEW YORK

HOOK AND EYE TAPE

Application filed March 30, 1927. Serial No. 179,408.

This invention relates to separable garment fasteners and particularly to that type thereof known as hook and eye tape. In the garment industry it has been the practice to use hooks and eyes secured at spaced intervals along a strip or tape of material which is sewed to the garment. Two general types of such tape have been used, one known as "riveted", and the other as "concealed", hook and eye tape. The riveted tape is characterized by the use of metallic rivets or grommets which pass through the tape material and the securing eyes of the fasteners for attaching them securely to the tape. As heretofore constructed the "concealed" type is characterized by the use of two strips of material one of which strips is approximately half the width of the other and is sewed along one of its longitudinal edges to the wider strip along the longitudinal center line thereof, thereby providing a pair of flaps along the lower half of the tape and a single thickness along the top half thereof. In the sewing of these two strips, gaps are left in the stitching to provide apertures through which the bill of the hook and the eye are passed in such a way that the co-operating locking or latching parts of the fasteners are exposed and extend transversely of the tape in juxtaposition to the single thickness of the wider strip at the upper half thereof, while the remaining parts of the fasteners are located in the space between, and are hidden or concealed by, the flaps. The fasteners are held secured to the tape either by making them a tight fit within the apertures or gaps left in the stitching thereof or are sewed directly to one or both of the flaps.

While both riveted and concealed tape have been used extensively for years, both types have objectionable features, among which the following may be noted: With the riveted type, the piercing of the holes for the large grommets used weakens the tape to such an extent that when a strong pull is exerted on the fasteners they frequently pull out tearing with them a section of the tape. The concealed type is also subject to the objection that the fasteners pull out and the further objection that the necessity for sewing the tapes

involves extra labor costs and the use of special machinery to perform the intermittent or gap stitching required.

The principal object of this invention is to provide a new and improved construction for a concealed hook and eye tape, and also for the fasteners intended to be incorporated therewith, by means of which the objectionable features above set forth will be obviated.

A further object is to provide a new and improved construction of such a hook and eye tape, the manufacture and assembly of which will be much simpler than that of the types heretofore used, and as a result the use of special expensive machinery will not be required and the cost of production will be lower.

Another object is to provide a novel construction for the tape, which is woven as a single one piece fabric of much greater strength and durability than the sewed tape heretofore used.

A further object is to provide a new and simple construction for the fasteners whereby they will also have greater strength and durability while at the same time they will be of a neat and attractive appearance.

These and other objects will appear more fully from the following more detailed description and by reference to the accompanying drawings forming a part hereof in which Fig. 1 is a front perspective view of a hook tape constructed in accordance with the principles of my invention; Fig. 2 is a similar view of an eye tape; Fig. 3 is an enlarged front elevation of a portion of the hook tape; Fig. 4 is a section on the line 4-4 of Fig. 3; Fig. 5 is a view similar to Fig. 3 of the eye tape; Fig. 6 is a section on the line 6-6 of Fig. 5; Fig. 7 is a perspective view of a hook fastener in its flat condition before the bill portion thereof is bent downwardly; Fig. 8 is a view similar to Fig. 7 of the hook fastener in its final form and Fig. 9 is a perspective view of the eye fastener.

As shown in the drawings, I provide a tape 10 woven to form an upper half 12 of a single thickness and a pair of lower flaps 13, 14 each of which is formed integral with the upper half 12 in the weaving of the tape. The

lower flaps 13, 14 are separated from each other at the outer or bottom edges thereof as clearly shown in Figs. 1 and 2 of the drawing. At the point of juncture of the two flap portions 13, 14, or, at least in one of the flap portions, say the flap 14, closely adjacent to the said juncture, a plurality of apertures 15 are provided, located at spaced intervals along the tape according to the desired spacing of the fasteners. These apertures 15 are also woven in the tape, that is to say, when the tape is woven in the loom the apertures are formed in a manner well known in the weaving art by dropping or otherwise omitting certain stitches, so as to leave a slot or slit which defines an aperture of the required dimensions to permit the passage therethrough of the securing or interengaging portions of the fasteners which are to be associated with the tape. In the weaving of the tape to form such apertures, that portion of the tape material which bounds the apertures may, if desired, consist of warp threads of extra strength or thickness. The use of warp threads of extra strength or thickness is, however, not absolutely essential, as the required strength may be secured by properly selecting the threads used for the weaving of the plain or uninterrupted portions of the tape and by the interlocking mesh thereof formed by the weaving. By forming the tape as a single piece of woven material having for the upper half portion a single thickness of material and having intermittently interwoven therewith the two flaps which form the lower portion, and furthermore by forming the apertures through which the securing portions of the fasteners project in the weaving of the tape, the final product secured is of much greater strength and durability, and also of much more attractive appearance than when the two lower flap portions are formed by sewing in the manner heretofore used.

In order to overcome fully, and to prevent absolutely, any pulling out of the fastener devices, such as occurs with the concealed type tape heretofore used, when a heavy strain or pull is placed upon the fasteners, I construct both the hook fasteners 16 and the eye fasteners 17 by punching, stamping or otherwise fashioning such fasteners from sheet metal material. As shown most clearly in Fig. 7, the hook fastener 16 is first stamped in the form of a flat substantially T-shaped member which consists of a tongue 16^a to provide the material for the bill of the hook and a cross bar 16^b which extends at right angle to the tongue 16^a. The cross bar 16^b is provided with a small struck-up protuberance 16^c located substantially in alignment with the longitudinal center line of the tongue 16^a. The tongue 16^a is then bent backwardly towards the cross bar 16^b to form the bill of the hook which bill extends substantially in parallelism with a space a short

distance from the cross bar 16^b, shown most clearly in Figs. 4 and 8 of the drawing.

In order to give added strength to the hook fastener and prevent bending thereof in a direction such as would increase the space between the bill and the cross bar, that portion of the tongue at the closed end of the bill is provided with a central depression 16^d formed by pressing such portion inwardly thereby defining a pair of upwardly projecting webs 16^e which act as reinforcing ribs for the closed end of the hook bill.

The eye fasteners 17 are also formed from sheet metal as above set forth and each eye fastener consists of an eye portion 17^a and a cross bar 17^b, the latter being similar in construction to the cross bar 16^b except that the protuberance 16^c is omitted. The eye portions 17^a of the eye fasteners are made somewhat greater in width than the slots or apertures 15 formed in the tapes, and each eye fastener has a reduced neck portion 17^c closely adjacent to the cross bar 17^b, the dimensions of the neck portions being such that such portions fit snugly within the apertures 15. The corners of the cross bars 16^b and 17^b are rounded sufficiently to prevent cutting, tearing, or piercing, of the tape.

After the tape has been woven, the fasteners are inserted in the apertures 15 in any suitable way, as for example, by pushing the bill portions of the hook fasteners or the eye portions of the eye fasteners through the apertures so as to leave the bill portions only and the eye portions only exposed while the cross bars 16^b and 17^b respectively, are located between the flaps 13, 14 and are concealed or hidden by such flaps. If it is desired to assemble the fasteners and tape by machinery, very simple apparatus will serve to perform such function, for example, the tape can be fed, preferably intermittently, while maintained under tension and, with the flap 14 extending at right angles to the upper half 12 of the tape, a small hook can then be inserted through each aperture to engage either a hook or an eye fastener which can be fed by any suitable means to a position adjacent to the respective aperture into which it is to be inserted, whereupon the feeding hook will engage with the bill of the hook fastener or the eye portion of the eye fastener, as the case may be, and thereafter will be moved backwardly through the aperture to pull the fastener into position and in locked engagement with the tape.

The manner in which the fasteners are caused to be assembled is immaterial as this may be done in any suitable way, for example, it may be found preferable to leave the tongues 16^a of the hook fasteners in the flat condition shown in Fig. 7 until after such tongues are inserted into the apertures of the tape and then to bend the tongue to the position shown in Fig. 8.

It will be readily apparent that a tape in which the flaps 13, 14 and apertures 15 are formed in the weaving can be made of any desired strength according to the strength of the threads employed in such weaving and that such a tape will have far superior wearing qualities and greater strength than the sewed tapes heretofore used. It will also be seen that the construction of the fastening members of sheet metal stampings will also result in the production of much stronger fasteners than when the fasteners are bent or formed from wire such as heretofore used for such devices, as obviously there can be no collapsing or bending of the sheet metal as a result of a pull upon the fasteners that would enable the fasteners to be pulled through the apertures.

I claim:

1. A separable fastening device consisting of a tape comprising a single thickness of material having at the lower end thereof a pair of flaps separated from each other at their outer edges and integral with said single thickness at their inner edges, one of said flaps being provided adjacent to its inner edge with a plurality of apertures, said single thickness, flaps and apertures being formed in the weaving of said tape, and a plurality of separable fasteners secured in interlocking engagement with the apertures of said tape, each stamped from a single piece of sheet metal and formed to provide a solid cross bar, and an extension projecting laterally therefrom, said extension being provided with means for being detachably engaged with a co-operating fastener, and said fasteners being secured in interlocking engagement with said tape with said extension projecting through said apertures and with said solid cross bar located between and concealed by said flaps.

2. A separable fastening device consisting of a tape comprising a single thickness of material, a pair of flaps separated from each other at their outer edges and integral with said single thickness at their inner edges, one of said flaps being provided adjacent to its inner edge with a plurality of apertures, and a plurality of separable fasteners in interlocking engagement with the apertures of said tape, each stamped from a single piece of sheet metal and formed to provide a solid cross bar, and an extension projecting laterally therefrom, said extension being provided with means for being detachably engaged with a cooperating fastener, and said fasteners being secured in interlocking engagement with said tape with said extension projecting through said apertures and with said solid cross bar located between and concealed by said flaps.

In testimony whereof I have hereunto set my hand.

LOUIS ROCKE.
